UNITED STATES PATENT OFFICE.

WARREN S. HILL, OF HYDEPARK, MASSACHUSETTS.

WINDOW ATTACHMENT.

SPECIFICATION forming part of Letters Patent No. 739,871, dated September 29, 1903.

Application filed May 23, 1903. Serial No. 158,415. (No model.)

To all whom it may concern:

Be it known that I, WARREN S. HILL, a citizen of the United States, residing at Hyde-park, in the county of Norfolk and State 5 of Massachusetts, have invented certain new and useful Improvements in Window Attachments, of which the following is a specification.

My invention relates to attachments for windows, and more particularly to metallic casings therefor.

It consists in the various features hereinafter described and more particularly claimed.

In the accompanying drawings, Figure 1 is 15 a perspective view of a portion of a window having two sashes to which one embodiment of my invention is applied, together with its frame, parts being broken away. Fig. 2 is an enlarged horizontal section taken in a plane 20 at the meeting-rails of the sashes. Figs. 3 and 4 are perspective views of a portion of the inner and outer casing-strips, respectively. Figs. 5 and 6 are similar views of reinforcing-strips for the above and for the intermediate casing-strips, respectively. Fig. 7 is a broken horizontal section through a window having a single sash to which another 25 form of my invention is applied, and Fig. 8 is a partial vertical section on the line 8 8 of Fig. 7.

Similar characters indicate like parts throughout the several figures of the drawings.

In devices of this class difficulty has been 35 encountered in securing a casing-strip which shall give a surface of contact with the sash resulting in free movement and at the same time freedom from rattling and complete exclusion of dust and which while having considerable resiliency to allow these results to 40 be effected will be sufficiently strong that it will not break in use. As a consequence metallic window-casings have been little used in practice. My invention overcomes such difficulties by the construction which will now be described.

The numerals 10 and 11 designate, respectively, the lower and upper sashes of a window movable in a frame 12 between the inner 45 cleat 13 and the outer projection 14. The sashes are more directly supported by my improved attachment, which is arranged as fol-

lows: Each sash is preferably provided with pairs of opposite grooves 15 15, extending vertically along the inner and outer faces near each edge and having their inner walls preferably curved, substantially as illustrated. With the inside groove of the lower sash contacts the casing-strip A. As here shown, this consists of a strip of thin sheet metal forming 55 at one part a base member 16, then bent substantially at right angles to furnish a stem 17, then in a cylindrical bead 18, extending in the opposite direction from the base, to furnish a member of double thickness, into engagement 60 with the sash-groove, and, finally, back parallel to the stem and base. Since to secure the requisite flexibility the material of which the casing is formed is quite thin, the base may be reinforced by a member 18', also of 65 sheet metal, bent over both sides of said base and, if desired, soldered or otherwise secured thereto. Openings 19 through the base and reinforcement, preferably elongated to permit lateral adjustment, receive screws 20 to 70 to secure the strip beneath the cleat 13, there being sufficient space between the edge of the cleat and the stem to allow some play of the strip.

The casing member between the two sashes 75 may conveniently consist of a double strip B, formed of two strips A' A', similar to A, but having their bases and contact-beads extending in the same direction. These separate strips may be secured together to form a 80 unitary member by a reinforcing-strip 21, common to both, extending beneath and bent over their bases. The stems of the strips A' may be separated by any desired distance 85 sufficient, for example, to occupy the same 90 space as the ordinary form of parting-bead, and thus provide for ready application of the device to old windows. To close the space between the stems and prevent the passage 95 of outer air through the channel thus formed, a filling member is provided, preferably consisting of an elastic block 22, of rubber or other suitable material, situated at the meeting-rails of the sashes and extending from them to the frame. Each block may be secured in place by a nail 23 driven through it into the frame or in any other convenient manner. Such a filling member serves not only as a closure, but also permits the spring-

strips to yield toward one another, as is desirable in this form of casing.

The groove in the outside of the upper sash is engaged by a casing-strip C, conveniently formed in the same general manner as one of the elements A' of the strip B, except that instead of the material extending from the bead parallel to the opposite side to form the double stem and base it projects at 24 at an angle to the stem, forming a guard, forced by the resiliency of the material with some pressure against the projection 14 and preventing access of air and dust. The reinforcing-strip may be applied in a manner precisely similar to that of the strip A, except that it here surrounds but a single thickness of the material. The openings 19 may be arranged the same in all parts of the casing. It will be understood that, as is usual in devices of this class, the sash contacts only with the strips at the sides and not with other portions of the frame.

Figs. 7 and 8 show the attachment applied to single-sash windows—such as are in use, for example, upon railroad-cars. Here, of course, the intermediate strip B is omitted and the sash 25 is supported between the strips A and C, engaging grooves in the inner and outer sides, respectively, they being formed and operating in the manner above described. In this connection or in any other it may be found expedient to reinforce the curved bead 18 to prevent its being dented or crushed. As here illustrated, this is effected by inserting within the bead a wire 26, which may be soldered in place.

In both applications of the device the sash-grooves preferably have a circular lateral contour or are of such form that the cylindrical bead of the casing may rock or rotate freely therein under the influence of any spring in the stem. This prevents strain from being brought upon the casing by the play of the sash.

With windows in some situations, as upon cars, particularly exposed to the ingress of dust, it may be found convenient to apply a guard-strip where the sash meets the sill. For this purpose one of the hereinbefore-described attachments may be used, being situated within a recess in one of the elements and having spring-contact with the other. As shown, the strip A is so used, its base being secured to the outside of the bottom of the sash, while the remainder projects into a recess 27 in the sash. Normally or when the window is open and the parts are not under tension the bead projects below the lower edge of the sash. Then when the sash is lowered the bead strikes the sill and is pressed back into the recess, Fig. 8. The tension in the stem holds the strip closely in contact to guard the opening throughout its entire length.

It will be seen that my improved attachment provides smooth continuous surfaces of

contact with the sash without projecting angles, which assures easy movement of the latter and freedom from cutting in or altering the shape of the groove, and that this surface of contact is relatively large and effective in excluding dust. Further, while the closed or continuous form of the contact-bead is such as to give the maximum strength and the base is obtained without sacrificing the elasticity of the spring-stem, which maintains the pressure of the strip against the sash and prevents rattling and the leakage of air and dust. The efficiency of the device in this latter respect is greatly enhanced by the spring-contact of the outer strip with the edge of the frame.

Having thus described my invention, I claim—

1. The combination with a window-sash and its frame, of a casing for said sash consisting of inner and outer strips secured to the frame, each strip comprising a base, a stem projecting therefrom and a contact-bead for coaction with the sash carried by the stem, and the outer strip also having a spring member contacting with a portion of the frame.

2. The combination with a window-sash and its frame, of a casing for said sash consisting of inner and outer strips secured to the frame, each strip comprising a base, a stem projecting therefrom and a contact-bead for coaction with the sash carried by the stem, the inner strip having said stem and base of double thickness.

3. The combination with a window-sash and its frame, of a casing for said sash consisting of inner and outer strips secured to the frame, each strip comprising a base, a stem projecting therefrom and a contact-bead for coaction with the sash carried by the stem, the inner strip having said stem and base of double thickness, and the outer strip having a spring member contacting with a portion of the frame.

4. The combination with a window-sash and its frame, of a casing for said sash consisting of inner and outer metallic strips secured to the frame, each strip furnishing a base and stem projecting therefrom, then bent to form a curved bead and then extending inwardly along the stem, the inner strip having this inward extension parallel to said stem.

5. The combination with a window-sash and its frame, of a casing for said sash consisting of inner and outer metallic strips secured to the frame, each strip furnishing a base and stem projecting therefrom, then bent to form a curved bead and then extending inwardly along the stem, the outer strip having this inward extension projecting at an angle from said stem.

6. The combination with a window-sash and its frame, of a casing for said sash consisting of inner and outer metallic strips secured to the frame, each strip furnishing a

base and stem projecting therefrom, then bent to form a curved bead and then extending inwardly along the stem, the inner strip having this inward extension parallel to said stem, and the outer strip having such inward extension projecting at an angle from said stem.

7. A window attachment comprising a base and a stem projecting therefrom bent to furnish a contact-bead extending from the stem at one side, and then inwardly along said stem and projecting therefrom at the opposite side from the contact-bead.

8. A window-casing comprising a metallic strip furnishing a base and a stem projecting therefrom, then bent to form a curved bead, then extending inwardly along the stem, and finally parallel to the base.

9. A window-casing comprising a metallic strip furnishing a base and a stem projecting therefrom, then bent to form a curved bead, then extending inwardly along the stem, and finally parallel to the base, and a reinforcing-strip surrounding both portions of the base.

10. A window-casing comprising a metallic strip furnishing a base and a stem projecting therefrom, then bent to form a curved contact-bead, and then extending inwardly along the stem but projecting at an angle from said stem.

11. The combination with a window-sash provided with a groove having a curved wall, of a casing having a spring-stem carrying a

curved bead coacting with the groove and free to rock therein.

12. The combination with a window-sash and frame, of a casing comprising a stem mounted upon the frame and coacting with the sash and a spring member projecting from the stem and contacting with a portion of the frame.

13. The combination with a plurality of window-sashes and their frame, of two separated casing-strips located between adjacent sashes, one of such strips coacting with each sash, and a filling member between the strips.

14. The combination with a plurality of window-sashes and their frame, of two separated spring casing-strips located between adjacent sashes, one of such strips coacting with each sash, and an elastic filling member between the strips near the meeting-point of the sashes.

15. The combination with a plurality of window-sashes and their frame, of two intermediate casing-strips having bases, and a reinforcing member common to both casing-strips surrounding their bases.

Signed at Boston, in the county of Suffolk and State of Massachusetts, this 18th day of May, 1903.
